UNITED STATES PATENT OFFICE.

HERMAN NIEMAN, OF CHICAGO, ILLINOIS.

WASHING-MACHINE.

1,279,139.

Specification of Letters Patent. Patented Sept. 17, 1918.

Application filed February 18, 1918. Serial No. 217,793.

To all whom it may concern:

Be it known that I, HERMAN NIEMAN, a citizen of the United States, residing at Chicago, in the county of Cook and State of Illinois, have invented certain new and useful Improvements in Washing-Machines, of which the following is a full, clear, concise, and exact description, reference being had to the accompanying drawings, forming a part of this specification.

This invention relates to improvements in washing machines and particularly to that class of machines wherein there is a rotating inner receptacle, such for instance as tubs of the character commonly used in steam laundries, hotel laundries and the like.

One of the objects of the invention is to provide improved means whereby the standard steam laundry tub may be divided into compartments, each compartment being adapted to contain a specific class of articles to be laundered, or the laundry belonging to one family or person, thereby saving time, trouble and expense in marking, recording and subsequently assorting such articles, and at the same time enabling all the clothes of a family or individual to be washed and kept together.

Another object is to provide an improved division member or partition that is removable and is also hingedly mounted at its rear end so that its forward end may be swung upwardly across the opening of the tub to permit access to the space in the tub beneath the partition.

Other objects and advantages will appear from the detailed description and claims to follow and from the nature of the apparatus itself.

For the purpose of disclosing my invention, I have illustrated one embodiment thereof in the accompanying drawings, in which—

Figure 1 is a vertical transverse sectional view taken on the line 1—1 of Fig. 2;

Fig. 2 is a substantially axial sectional view taken on the line 2—2 of Fig. 1;

Fig. 3 is a sectional detail on the line 3—3 of Fig. 1; and

Fig. 4 is a detailed sectional view showing the means for holding the dividing member in raised position.

In the embodiment of the invention illustrated, there is the usual stationary cylindrical casing 5, formed of heavy wood staves and provided with an opening

through which access may be had to the interior of the casing, this opening being covered by a sliding cover plate 7, which may be closed when the tub is in operation. 60 Mounted within this casing, which is large enough to contain what may be termed two rotating tubs, are a pair of rotating tubs preferably constructed with a pair of circular heads 8 having mounted thereon supporting shafts 9 journaled in the heads 10 of the outer casing. One of these shafts, on the exterior of the casing, may be provided with a suitable driving gear 50 or be connected otherwise to the tub-driving mechanism. Secured to these heads 8 are a series of staves 11 thereby forming an elongated wood cylindrical rotating tub, mounted and rotating within the casing. These staves 11 are placed adjacent one another and are provided with suitable openings 12 to permit the hot suds or steam to enter the inside of the tub from the outer casing. This tub cylinder is divided in half, or into two tubs, by means of a central circular head 13. 70 Straps 14 surround the tub to bind all parts together. At regular intervals in the circumference of the tubs are provided baffles 15 projecting radially into the tub or tub cylinder. These baffles are secured in place 80 by keepers 16 attached to the walls 8 and 13 (Fig. 3), and provide projections which catch the clothes and serve to lift the same as the tub is rotated, until the clothes drop or roll off back into the hot suds. Each of the tubs is provided with a door 17, preferably consisting of a section of the casing cut out and hinged at 18 so that when the door reaches a position opposite the opening 6 its lower edge may be raised to permit access to the interior of the tub. This door is 90 preferably made of the same width as the tub and is held shut in operation by means of suitable slide bolts 19.

It is desired on the part of laundries in 100 certain instances to separate the clothes to be laundered into different batches and to keep them so separated during the laundering process, as, for example, the laundry of one family. Heretofore it has not been 105 practical to wash the clothes economically in this manner. The laundry tubs are usually so large that it does not pay to wash a small batch of clothes in one tub. To obviate the objection, such separate batches have been 110 placed in bags, but this is objectionable for various reasons.

In order to overcome this objection, I provide a means whereby the tubs may be divided diametrically into compartments, this means being preferably adaptable for use in connection with the standard form of laundry tub now in use, and so designed as to be applied to the standard tub without changing the construction of the tub or without disassembling it, and readily removable so that the tub can still be used in the old way.

In order to so divide the tubs into sections, a removable dividing member or partition is provided, which preferably is in the form of a frame comprising two side members 20 and the end members 21, between which are secured a plurality of round bars or rods 22. These rods may be placed close together or may be suitably spaced apart as desired. These rods provide on the opposite faces of the division member thus formed a corrugated rubbing surface for the clothes, similar to the ordinary hand wash-board. This frame is supported in position in the tub between and in the plane of two oppositely disposed baffles 15. To the opposite sides respectively of the side bars 20 at one end of the frame are secured a pair of metal strips 23 having splayed projecting ends that straddle one of the baffles 15, as clearly shown in Fig. 1, whereby this end of the frame is held in position so that it will not move during the rotation of the tub; at the same time it is hingedly or pivotally, as well as removably, mounted so that its front or opposite end may be raised. The opposite end of the frame is supported on the opposite baffle 15 through the agency of flat metal strips 24 secured to the upper sides of the side bars 20 and projecting beyond the ends of the latter sufficiently to rest directly on the baffle 15. To prevent the frame from becoming displaced at this end, I provide stops or abutments 25 on the inner face of the door 17, which, when the door is closed, take a clamping position over strips 24 so that the front end of the frame is held between these abutments 25 and the baffle 15. The frame is thus locked in position from all sides and will not become displaced during the rotation of the tub. At the same time, the frame is hingedly mounted in the tub so that what may be termed its forward end may be raised, as shown by dotted lines in Fig. 1, to permit access to the bottom compartments of the tub. I use the term "bottom compartment" to describe that portion of the tub which is at the bottom when the tub is in its normal position, that is the position with the door 17 opposite the opening 6. In this position with the door 6 open, the frame or division member may be raised to permit placing clothes in or removing them from the bottom compartment, the frame being held in its raised position dur-

ing these operations by means of a suitable spring catch 26 formed in one head of the tub, as shown in detail in Fig. 4. After the clothes have been deposited in the bottom of the tub, the frame or division member may be lowered and an additional batch of clothes deposited in the top of the tub, after which the door 17 is closed and the cylindrical tub started to rotate in the usual manner and at the usual speed. It will be seen that as the tub rotates, the clothes will be picked up from the bottom by the baffles 15, eventually dropping by gravity on one end of the division member and sliding along this division member toward the opposite end and bottom of the tub again, so that a rubbing action of this division member on the clothes constantly takes place during the washing operation.

Of course the invention may be applied to single tubs as well as to double ones like those shown, and to various forms and types of tubs, and to tubs of various materials, and the division member itself may be constructed in various ways and of various materials and be secured in position in the tubs in various ways, all without departing from the spirit or scope of the invention as set forth in the following claims.

I claim:—

1. In a laundry tub, the combination with a casing, of a rotatable tub mounted within said casing and having an opening to permit access to the interior thereof, and a division member extending diametrically entirely across said tub, said member being removably mounted therein and hingedly supported at the end opposite said opening, the end adjacent said opening adapted to be raised and lowered for access to both compartments of the tub.

2. In a laundry tub, the combination with a rotatable cylindrical casing having an opening in its circumference and provided with internal baffles, of a removable partition dividing said casing diametrically into compartments, said partition at one end hingedly engaging one of said baffles and at its other end supported by a diametrically opposite baffle, and means for clamping said other end of the partition on said baffle.

3. In a laundry tub, the combination with a rotatable cylindrical casing having an opening in its circumference and provided with internal baffles, of a cover for said opening, a removable partition dividing said casing diametrically into compartments, said partition at one end hingedly engaging one of said baffles and at its other end supported by a diametrically opposite baffle, and means on said cover for locking said partition in place on said last named baffle when the cover is closed.

4. In a laundry tub, the combination with a rotatable cylindrical casing having an

- opening in its circumference and provided with internal baffles, of a removable division member extending diametrically across said casing, said division member having at one 5 end a pair of forwardly projecting splayed strips straddling one of said baffles whereby it is loosely and removably hinged to the latter, and means to hold the other end of said division member stationary.
- 10 5. In a laundry tub, the combination with a rotatable cylindrical casing having an opening in its circumference and provided with internal baffles, of a removable division member extending diametrically across said 15 casing, said division member having at one end a pair of forwardly projecting splayed strips straddling one of said baffles whereby it is loosely and removably hinged to the latter, and at its other end a rearwardly projecting strip adapted to rest upon a diametrically opposite baffle.
6. In a laundry tub, the combination with a rotatable cylindrical casing having an opening in its circumference and provided with internal baffles, of a hinged cover for 25 said opening, a removable division member extending diametrically across said casing, said division member having at one end a pair of forwardly projecting splayed strips straddling one of said baffles whereby it is 30 loosely and removably hinged to the latter, and at its other end a rearwardly projecting strip adapted to rest upon a diametrically opposite baffle, and a stop on the free edge of said cover adapted, in the closed position 35 of the latter, to overlie said last named strip and clamp it on said baffle.

HERMAN NIEMAN.
